James J. Wynne
W. E. Beatty Atty.
by

UNITED STATES PATENT OFFICE.

JAMES J. WYNNE, OF ROSELLE PARK, NEW JERSEY, ASSIGNOR TO WESTERN ELECTRIC COMPANY, INCORPORATED, OF NEW YORK, N. Y., A CORPORATION OF NEW YORK.

SWITCH-CONTROL CIRCUITS.

Application filed April 8, 1922. Serial No. 550,581.

To all whom it may concern:

Be it known that I, JAMES J. WYNNE, a citizen of the United States, residing at Roselle Park, in the county of Union, State 5 of New Jersey, have invented certain new and useful Improvements in Switch-Control Circuits, of which the following is a full, clear, concise, and exact description.

This invention has to do with electrical 10 switching devices and control circuits therefor, and relates more particularly to an arrangement whereby circuit connections extending between a circuit controller and devices under control thereof may be transferred to a second circuit controller without 15 any harmful interference with the operation of the aforementioned devices.

In automatic telephone systems of the type 20 shown, for example, in United States Patent No. 1,395,977, issued November 1, 1921 to F. A. Stearn and F. J. Scudder, so-called pulse machines are employed, the function 25 of which is to assist in the transfer of the registrations set up by calling subscribers, through the operation of their calling dials, 30 from the number registers in the subscribers' senders to the translator register relays, as clearly described in the aforementioned patent.

These pulse machines constitute an extremely 35 vital part of the automatic telephone installation as each of them serves a very large number of subscribers and is subjected to long periods of continuous service. Should any serious trouble occur in any 40 of these machines, there would be danger of disrupting the service of all the subscribers' lines associated therewith. In order to make adequate provision for possible trouble in this connection, emergency pulse machines 45 are provided and it becomes necessary to provide suitable arrangements for transferring the connections from the translator register relays, from one pulse machine to another, and in effecting such transfers, to avoid any 50 harmful interference with the operation of the translator register relays such as might result in improper extension of telephone connections.

It is, therefore, an object of this invention 55 to provide suitable arrangements in association with a transfer switch whereby the latter is prevented from being operated at such times as would result in disrupting regis-

tions in progress on the translator register re- 55 lays.

A further object of the invention is to provide signaling means for apprising an attendant when the transfer switch may be operated. 60

In accordance with the objects stated, the principal feature of the invention relates to the provision in association with a locking transfer switch of electromagnetic releasing means therefor under the control of a starting circuit which is responsive to the movement of a pulse machine or like device whereby the releasing means cannot be energized until the pulse machine has completed a predetermined extent of operation following the 70 operation of a starting switch.

It is thought that the invention will be more readily understood from the following detailed description, having reference to the accompanying drawing. In the drawing, 7 75 and 8 each represent, in developed form, the surface of a cylindrical drum of a pulse machine, each being independently and continuously rotatable in the direction indicated by the arrow thereon. Each drum has a metallic collecting ring 9 which is electrically connected to the several metallic segments 10, 11, etc., shown thereon. The space between the segments is preferably filled with a suitable insulating material on which the several 80 brushes 12, etc. bear when not in contact with the metallic segments.

A multiple contact switch 13 is provided for transferring the circuit connections from one pulse machine to another and, in the 90 drawing, pulse machine drum 7 is shown so connected. The operating handle 14 is provided with a sector-shaped portion 15 having two notches 16 for engagement by the dog 17, carried by the armature of the electromagnet 18. When the dog 17 is in engagement with either of the notches 16, the switch is locked and cannot be thrown into its alternate position without first energizing the release magnet 18. A switch of this 95 type which may be employed herein is shown in the application of H. T. Martin, Serial No. 402,867, filed August 11, 1920.

The six bank terminals 19, 33, etc., and brushes 20, 32, etc., are those of a translator switch which may be of the type shown in United States Patent No. 1,123,696, issued January 5, 1915, to E. B. Craft and

J. N. Reynolds. These brushes are arranged in sets, one being shown, and are movable vertically, in unison, to select sets of bank terminals under the control of the subscribers' register senders. The provisions for controlling the translator switches are not described herein as such a description is not thought to be essential to a clear understanding of the present invention, but a complete description thereof may be found in Patent No. 1,395,977 to F. A. Stearn and F. J. Scudder, previously mentioned.

Relays 21, 22, 23, 24, 25 and 26 comprise a partial showing of a set of translator register relays, a complete description of which may also be found in Patent No. 1,395,977.

The primary function of the pulse machine is to effect the operation of relays 24, 25, 26, etc., in various combinations in accordance with the selections of the translator switches which in turn are controlled by the subscribers' register senders, the latter being set by the calling subscribers in accordance with the office and numerical designations of called subscribers' lines. A complete set of translator register relays comprises a considerable number of relays similar to relays 24, 25 and 26 which may be operated in a large number of combinations, but, for the purpose of the present description, it may be assumed that the particular connection in progress requires the setting of relays 25 and 26 in addition to other relays which are not shown and that the translator brushes 20, etc., have accordingly been set on the bank terminals shown. The contacts 27, 28, 29, 30 and 31 are controlled by one or more sequence switches which may be of the type shown and described in United States Patent No. 1,127,808 to Reynolds, et al., issued February 9, 1915, and for the purpose of this description it will be assumed that these contacts are opened and closed at the proper times. With sequence switch contact 28 closed, an obvious circuit is established for energizing relay 51 which closes its contacts thereby establishing circuit connections from relays 21, 22 and 23 to the brushes of the pulse machine as follows: from ground, through relay 21, conductor 30, armature and front contact of relay 51, conductor 31, brush 32 and terminal 33 of the translator switch bank, conductor 34, cross connection on terminal block 35, conductor 36, wiper 37 of the transfer switch 13 and brush 38. When the brush 38 makes contact with segments 39 or 40 of the pulse machine, the foregoing circuit is extended through collector ring 9, brush 41, wiper 42 of the transfer switch to battery and ground, and relay 21 is energized, closing its contacts. Since there are two segments 39 and 40 only, on that portion of the circumference of the pulse machine drum corresponding with brush 38 relay 21 will be energized

twice in the course of each complete revolution of the drum and will release immediately upon the brush 38 disengaging either segment. Similar circuits may be traced for relays 22 and 23 extending to brush 43 with which is associated a portion of the pulse machine drum having only one segment 44. Therefore, relays 22 and 23 will each be energized once only for each revolution of the drum.

When relay 21 is momentarily energized, a circuit is extended from ground through relay 24, conductor 45, front contact and armature of relay 21, conductor 46, wiper 47 of the transfer switch and brush 48 of the pulse machine. Brush 48 does not engage segment 11² at a time when relay 21 is energized as will be evident from the fact that segment 11² is not in alignment with either segment 39 or 40, and therefore, no circuit can be completed for operating relay 24 with the assumed setting of the translator switch. However, upon tracing the corresponding circuits of relay 25 to brush 49, and relay 26 to brush 50, it will be apparent that these circuits are each extended through to battery at a time when relay 21 is energized, it being noted that segment 11 corresponds in position with segments 39 and 44 and segment 11' corresponds with segment 40. Relays 25 and 26 operate and lock up over circuits extending from ground through their left-hand windings and left-hand armatures and contacts and sequence switch contact 27 which is closed at this time to grounded battery.

Immediately after the set of translator switch brushes including brushes 20, 32, etc., were positioned on the bank terminals shown, a sequence switch in the subscriber's register sender was moved under the control of circuits, not here shown, to close contacts 28, 29, 30 and 31. With contact 30 closed, a circuit is extended from ground, through stepping relay 52 to brush 12 of the pulse machine. Six segments 10 are provided on the pulse machine drum for cooperating with brush 12 and when the latter engages any of these segments, a circuit is completed from grounded battery, through wiper 42, brush 41, collecting ring 9, the engaged segment 10, brush 12, wiper 53, conductor 54, contact 55 of key 56, conductor 57, relay 52, conductor 58, back contact and armature of counting relay 0' and to ground through contact 30 of the sequence switch cam. Relay 52 is momentarily energized in this circuit six times in the course of one complete revolution of the drum 7. Upon the first energization of relay 52, a circuit is closed from ground, through sequence switch contact 29, contact and armature of relay 52, upper armature and front contact of relay 51, conductor 60, conductor 61 at the No. 6 counting relay, armature and back

contact of the counting relay No. 6', through the No. 6 counting relay to grounded battery. Counting relay No. 6 energizes in this circuit and locks up over a circuit extending through the No. 6' counting relay, its own armature and contact, and sequence switch contact 31 to ground. Counting relay No. 6', however, does not energize in this circuit due to the fact that it is shunted by the ground through contact of stepping relay 52.

As soon as brush 12 moves off the first segment 10, relay 52 is momentarily deenergized and opens its contact thereby removing the ground from conductor 61 whereupon counting relay No. 6' is energized in series with counting relay No. 6 and attracts its armature thereby extending the previously traced interrupter circuit to the No. 5 counting relay which in turn is energized in the same manner as counting relay No. 6 as soon as relay 52 is again operated. The foregoing operation repeats itself until the counting relays have been satisfied, whereupon counting relay 0' is energized thereby breaking the back contact of its outer armature which is in the circuit of stepping relay 52 and closing the front contact of its inner armature thereby completing a circuit from grounded battery, through relay 62, upper inner armature and front contact of relay 51 and conductor 63 to ground, through the front contact and inner armature of counting relay 0'. The stepping relay 52 ceases to operate and relay 62 operates to open the circuit of relay 51 and locks up over a circuit including sequence switch contact 28. Relay 51 deenergizes thereby opening the circuits of relays 21, 22 and 23. In order to satisfy the counting relays, seven energizations of relay 52 are required and since there are only six segments 10 evenly distributed around drum 7, it is evident that approximately one and one-sixth turns of the drum are required for a complete operation. This provision is made to ensure that not less than a complete turn of the drum will be made between the time the translator register relays are connected thereto and the time when they are disconnected therefrom. After the translator switch is restored to normal, sequence switch contact 31 is opened and the counting relays restored.

During the hours of heavy traffic in a busy automatic telephone office, the calls come in very rapidly so that at any given moment there may be a considerable number of sets of translator register relays being operated by a single pulse machine in the manner previously described. It is desirable to avoid disrupting the operation of setting these relays when it becomes necessary to operate the transfer switch 13, as otherwise the telephone connections con-

cerned would not be established as intended. The transfer switch, therefore, is arranged to be locked in each of its operative positions as previously stated and cannot be unlocked except through operation of the circuit hereinafter described whereby harmful interference with the setting of the translator register relays is obviated.

When a maintenance attendant at the central office wishes to operate the transfer switch 13, he first operates key 56 which opens contact 55 in the circuit of stepping relay 52, closes contact 64 providing ground for the special set of timing counting relays shown enclosed in the dot and dash rectangle and closes contact 65 in the circuit of relay 66. The circuit for relay 66 may now be traced from ground, relay 66, contact 65, conductor 67, wiper 68, and brush 69 of the pulse machine. Cooperating with the latter brushes are two segments 70 and 71 which are disposed on diametrically opposite sides of the drum. Therefore, when brush 69 makes contact with either of the segments 70 and 71, a circuit is completed from grounded battery, through the pulse machine to relay 66 and the latter is energized. One complete rotation of the drum 7 accordingly causes relay 66 to be energized twice. Upon the first operation of relay 66 a circuit is completed from grounded battery through conductor 72, counting relay B, armature and back contact of counting relay B', to ground through the armature and contact of relay 66. Counting relay B energizes in this circuit and establishes a locking circuit for itself extending as follows: grounded battery, conductor 72, counting relay B, counting relay B', contact and armature of counting relay B, conductor 73 to ground through contact 64 of key 56. Counting relay B' does not immediately energize in this circuit as it is shunted by the ground from the armature and contact of relay 66, but as soon as relay 66 deenergizes, counting relay B' energizes in series with counting relay B. When brush 69 encounters the next segment 70 or 71, the circuit from ground at relay 66 is extended through the armature and front contact of relay B', the armature and back contact of counting relay A' and counting relay A to battery. Counting relay A energizes in this circuit and is followed by counting relay A' as soon as relay 66 deenergizes. The operation of the special counting relays up to this point has required substantially a complete revolution of the drum 7 which would generally be sufficient to complete the operation of setting the translator register relays which may have been started when key 56 was operated, but due to the fact that segments 70 and 71 have an appreciable circumferential dimension, it is quite possible

to complete the setting of the special counting relays up to this point without the drum 7 having quite made a complete revolution following the operation of key 56. 5 So, for that reason it is provided that the drum 7 shall make substantially one and one-half revolutions following the operation of key 56 thereby ensuring that translator register relay settings in program 10 shall be completed. When brush 69 again engages segment 70 and 71, relay 66 is energized as before and the circuit from ground through the armature and contact of relay 66 is extended through the armatures and front contacts of counting relays A' and B' which were previously operated, and normal contact and winding of relay 74 to grounded battery. Relay 74 energizes in this circuit and closes a circuit from 15 grounded battery through release magnet 18, key 77, and signal lamp 75 in parallel, conductor 76, contact and left-hand armature of relay 74 to ground. Lamp 75 lights and the release magnet 18 energizes in this 20 circuit withdrawing dog 17 from the notch 16 with which it was engaged. The lighting of lamp 75 indicates to the maintenance attendant that the transfer switch is unlocked and may be thrown to its alternate 25 position thereby disengaging the drum 7 and connecting in drum 8. Following the operation of the transfer switch key 56 is released and the timing counting relays and magnet 18 are released, the magnet 18 30 locking the transfer switch in its alternate position.

Key 77 is provided for use in special emergencies as, for instance, in the event that the transfer switch should fail to unlock following the operation of key 56. 40 Such an emergency might arise due to the driving motor of the pulse machine breaking down and from other causes. It will be readily seen from the drawing that an operation of key 77 closes a circuit directly through release magnet 18 to ground 45 through contact 64 of key 56, thereby unlocking the transfer switch 13. After a transfer switch has been operated through the use of the emergency key 77, key 56 50 is kept in its operated position until lamp 75 lights, thus allowing time for a complete cycle of operation of the newly connected pulse machine before stepping relay 52 is 55 permitted to start counting off.

In the event of a new selection being established at one of the translator switches during the interval between the operation of key 56 and its restoration following the 60 operation of the transfer switch, no damage can be done because relay 62 cannot be energized until the counting relays under the control of stepping relay 52 have been satisfied and as previously pointed out, it requires slightly more than a complete ro-

tation of a pulse machine drum with contact 55 closed to satisfy the counting relays. Thus, it will be seen that the translator register relays associated with the last mentioned selections will have access to the 70 newly connected pulse machine for the full period of time required, and it will also be seen that all of the sets of translator register relays which were in the course of being set at the time key 56 was operated will be completely set before transfer switch 13 can be thrown into its alternate position.

What is claimed is:

1. In combination, a switch having a plurality of operative positions, means for locking said switch in at least one of said positions, an electromagnet for releasing said switch whereby it may be operated, a circuit for said electromagnet including a source of current and a normally open contact, a normally open starting circuit, and a set of counting relays for controlling said normally open contact, said counting relays being under the control of said starting circuit and operable to interpose a delay in the closure of said normally open contact following the closure of said starting circuit.

2. In combination, a switch having a plurality of operative positions, means for locking said switch in at least one of said positions, releasing means for said switch, a starting key for said releasing means, means for interposing a predetermined delay in the operation of said releasing means following an operation of said key, and a signal for indicating when said releasing means is operated.

3. The combination with an electroresponsive device, of a circuit interrupter for controlling the operation of said electroresponsive device, a circuit including a source of current interconnecting said electroresponsive device and said interrupter, a transfer switch in said circuit, a second circuit interrupter, said transfer switch being adapted for transferring the control from said first interrupter to said second interrupter, means for locking said transfer switch in its operative positions, and means for preventing the unlocking of said transfer switch during the course of operation of said electroresponsive device.

4. In combination, a plurality of circuit interrupters, circuit connections therefor, a switch for transferring said circuit connections to any of said interrupters individually, means for locking said switch in any of its operative positions, electromagnetic releasing means for said locking means, a circuit and source of current for said releasing means, a starting switch for said last mentioned circuit, and means for delaying the operation of said releasing means.

after the operation of said starting switch until the connected one of said interrupters shall have completed a predetermined extent of operation.

- 5 5. In combination, a plurality of electrical devices, circuit connections therefor, a switch for transferring said circuit connections to any of said devices individually, a lock for holding said switch in any of its operative positions, electromagnetic releasing means for said lock, a circuit including a normally open contact for said releasing means, a starting circuit for closing said normally open contact, and means responsive to the movement of the connected one of said electrical devices for delaying the closure of said normally open contact until said device shall have completed a predetermined extent of operation following the closure of said starting circuit.

- 10 6. In combination, a plurality of circuit interrupters, a group of relays operable in different combinations, circuit connections from said relays, a switch operable to transfer said circuit connections from one to another of said circuit interrupters, a lock for holding said switch in each of its operative positions, electromagnetic releasing means for said lock, a circuit including a normally open contact for said releasing means, a starting circuit for closing said normally open contact, and a group of counting relays associated with said starting circuit responsive to the movement of the connected one of said circuit interrupters for delaying the closure of said normally open contact until said circuit interrupters shall have completed a predetermined extent of operation following a closure of said starting circuit.

- 15 7. In combination, a plurality of circuit interrupters, an electroresponsive device operable by either of said interrupters, circuit connections extending from said electroresponsive device, a switch for extending said circuit connections to either of said circuit interrupters individually, a lock oper-

able to hold said switch in either of its operative positions, electromagnetic releasing means for said lock, a circuit for said releasing means including a normally open contact, a circuit including a series of counting relays for closing said normally open contact, and a normally open starting circuit for controlling said counting relays in accordance with the movement of the connected one of said circuit interrupters whereby said circuit interrupter shall have completed a predetermined extent of operation following a closure of said starting circuit before said releasing means is energized.

20 8. A manually operated switch having a plurality of operative positions, a locking member to hold said switch in any of its operative positions, an electromagnet, a timing device, a starting circuit for said timing device, a key, means to complete the starting circuit for said timing device under the control of said key, a circuit for said electromagnet controlled at the contacts of said timing device, and means to actuate said locking member to release said switch under the control of said magnet.

25 9. A plurality of electro-responsive devices, a timing device individual to each electro-responsive device, a common device operable to control said electro-responsive devices, means for connecting one or more of said electro-responsive devices to said control device, means under the control of said timing device for disconnecting said electro-responsive device from said control device, a common timing device, and means for arresting the operation of said individual timing device and substituting said common timing device to delay the disconnection of said electro-responsive device from said control device for a predetermined period.

30 40 45 50 55 60 65 70 75 80 85 90 In witness whereof, I hereunto subscribe my name this 1st day of April, A. D. 1922.

JAMES J. WYNNE.
